UNITED STATES PATENT OFFICE.

LUDWIG KÜHN, OF CHARLOTTENBURG, NEAR BERLIN, GERMANY, ASSIGNOR TO WESTINGHOUSE ELECTRIC & MANUFACTURING COMPANY, A CORPORATION OF PENNSYLVANIA.

MODULATION SYSTEM.

Application filed September 2, 1921, Serial No. 498,185, and in Germany December 1, 1920.

This invention relates to radio sending systems of the type using vacuum tubes as generator and modulator. It is an object of this invention to provide a means by which 5 the modulation of the signaling energy may be more readily and certainly accomplished.

More specifically stated, the invention is applicable to a system in which current changes in the modulator are accompanied 10 by current changes in the generator and it is an object of this invention to cause the current changes in the modulator to produce potential changes upon the grid of the generator in a sense that will reenforce the 15 current changes in the generator.

Other objects of the invention and details of the structure will be apparent from the following description and the accompanying 20 drawings in which the single figure is a dia- 20 grammatic view showing the connections which embody my invention.

The system includes an antenna 1 having an inductor 2, an adjustable condenser 3 and a ground connection 4. This antenna is 25 energized by a thermionic device 5, the plate circuit of which includes a coil 6 inductively coupled to the coil 2. An adjustable condenser 7 provides for tuning the circuit comprising the coil 6 and the condenser 7. 30 The grid connection of the tube 5 includes an oscillating circuit, comprising the coil 8 and the adjustable condenser 9. When the condensers 7 and 9 are properly adjusted, there is a regenerative action in the tube 5, 35 due to the coupling afforded by the tube itself between the two tuned circuits.

The energy for sustaining the oscillations produced by said regenerative action is obtained from a battery 10. This battery 40 is connected to the plate circuits of the generator tube 5 and a modulator tube 11. The connection from the positive side of the battery to the anodes of the tubes 11 and 5 includes an inductance coil 12 having an 45 iron core. The purpose of this coil is to prevent any sudden change in the total output of the battery 10.

The connection, common to the two plate 50 circuits of the tubes 5 and 11, includes a condenser 13 and goes to a point 14 in the connection between two substantially equal resistors 15 and 16. The negative pole of the battery 10 is connected to the same point 14. A condenser 17 is supplied in shunt

with the resistance 15 and the condenser 18 55 in shunt with the resistance 16. The end of the resistor 15 opposite the point 14 is connected to the filament of the vacuum tube 5 and the end of the resistor 16 opposite the point 14 is connected to the filament of 60 the bulb 11. The grid of the bulb 11 is connected to the filament and this connection includes the primary 19 of a transformer, the secondary of which is connected to a telephone transmitter 20. The grid connection 65 from the grid of the bulb 5 ends in an adjustable contact on the resistor 16, near the end thereof opposite the point 14. This connection includes the oscillating circuit 70 8-9 already described.

In the operation of the device, sounds entering the telephone transmitter 20 produce changes in the potential of the grid in the bulb 11 and so cause changes in the conductivity of this bulb. The current flowing 75 through the bulb thereupon changes and, since the total current is kept from changing by the inductor 12, changes of opposite sign occur in the current through the bulb 5. These changes are superposed upon the 80 oscillations due to the regenerative action already described. The energy delivered to the antenna therefore comprises oscillations, of the frequency determined by the tuning of the condensers 7 and 9, modulated by the 85 action of the telephone transmitter and the bulb 11, just explained. Obviously the condensers 7 and 9 are adjusted so that the two oscillating circuits are tuned to the same frequency and, for best results, the condenser 3 is adjusted so that the antenna is 90 also tuned to this frequency.

Consider the action at a time when the current in the plate circuit of the bulb 11 is increasing in response to action of the telephone transmitter. This increase is accompanied by an increase in the potential drop over the resistor 16. The point 14, since it is connected to the negative end of the battery 10, may be regarded as having a constant potential. The filament of the tube 5, because the resistance of 15 is equal to the resistance of 16, is at the same potential as the right hand end of the resistor 16. The grid of the bulb 5, since it is connected to an intermediate point of the resistor 16, is therefore, negative with respect to the filament, by an amount dependent upon the 100 105

drop through the part of the resistor 16 at the right of the adjustable contact. The increase in this drop causes the grid in the tube 5 to become more negative, and negative potential upon the grid tends to prevent flow in the plate circuit of the grid 5. Increase in flow through the plate circuit of the bulb 11 is accompanied by diminution of the flow through the plate circuit of the bulb 5 and the action just explained makes this diminution greater. This increase in the effective resistance of the bulb 5, in its turn, causes a further increase in the flow in the plate circuit of the bulb 11. It is, therefore, clear that the changes set up by the telephone transmitter 20 give rise to a cycle of events that tends to produce further changes in the same direction. The modulation is thus greatly increased and the arrangement, therefore, constitutes a very sensitive arrangement for sending.

When the current through the bulb 11 increases and the current through the bulb 5 decreases, the drop over the whole of the resistor 15 is less than that over the whole of the resistor 16. If the connection from the grid of the bulb 5 were very close to the right hand end of the resistor 16, this fact would overbalance the matters just explained. If the adjustable connection of the resistor 16 were at the left hand end, no change whatever in the potential of the grid of the tube 5 would be produced by the drop in this resistor. It is, therefore, obvious that the extent to which added sensitivity is secured can be regulated by adjusting the connection along the resistor 16.

It will be evident to those skilled in the art that many variations may be made in the details of the structure and that the invention is capable of other embodiments beside the one illustrated; therefore, I do not intend the patent to be limited except as necessitated by the prior art and indicated by the claims.

I claim as my invention:

1. In combination, a pair of vacuum-tube devices, each having a plate circuit, a source

of direct-current energy connected to said plate circuits in parallel, said connection including a resistor, a condenser in parallel to said resistor, and a connection from the grid circuit of one of said vacuum-tube devices to an adjustable point on said resistor. 50

2. In combination, a thermionic oscillation generator and a thermionic modulator having their plates connected in parallel, and means, including a resistor in the plate circuit of said modulator, for controlling the grid potential in the generator. 55

3. In a radio-signal-sending system, a pair of thermionic devices, a battery for energizing said devices, a connection between the cathodes of said devices, said connection including a resistor, and means for keeping 65 the mid-point of said resistor at the potential of the negative end of said battery.

4. In a radio-signal-sending system, a pair of thermionic devices, a battery, a condenser, a connection between the plate circuits of 70 said thermionic devices, a connection between the cathodes of said thermionic devices, said last named connection including a resistor, said battery and condenser each being connected between the mid-point of 75 said resistor and said first named connection.

5. In combination, two thermionic devices, each having a plate circuit, two resistors one in each of said plate circuits, two condensers, one in shunt to each of said resistors, and a connection from the grid of one of said thermionic devices to an intermediate point in the resistor associated with the other of said thermionic devices. 80

6. In a radio system, two vacuum-tube devices, a source of direct-current potential connected to the plate circuits of said vacuum-tube devices in parallel, a condenser connected in parallel to said two plate circuits and connections from the grid circuit 90 of one of said vacuum-tube devices to a point of intermediate potential in the plate circuit of the other of said vacuum-tube devices. 85

In testimony whereof I affix my signature.

DR. ING. LUDWIG KÜHN.
